UNITED STATES PATENT OFFICE.

JOHN F. O'CONNOR, OF CHICAGO, ILLINOIS, ASSIGNOR TO WILLIAM H. MINER, OF CHAZY,
NEW YORK.

CAR CONSTRUCTION.

1,307,308.

Specification of Letters Patent. Patented June 17, 1919.

Application filed October 23, 1916. Serial No. 127,091.

To all whom it may concern:

Be it known that I, JOHN F. O'CONNOR, a citizen of the United States, residing at Chicago, in the county of Cook and State of Illinois, have invented a certain new and useful Improvement in Car Construction, of which the following is a full, clear, concise, and exact description, reference being had to the accompanying drawings, forming a part of this specification.

This invention relates to improvements in car construction.

As is well known, cars in actual service are subject to enormous shocks, particularly under buffing. It has been common practice heretofore to provide shock absorbing mechanism of necessarily limited capacity and so arranged that the shocks are transmitted to a pair of center sills over a relatively limited area. The capacity of said shock absorbing mechanisms is not only limited by the space within which they must be confined, but also because of the fact that an easy action must be provided in order to absorb the small shocks as well as heavy shocks. The disadvantage of former types of shock absorbing arrangements resides in the fact that the stresses are transmitted to two sills of the car only over a limited area and unusual or excessive shocks are transmitted to the car after the shock absorbing device has gone solid.

It is the object of the present invention to provide an arrangement of car construction and shock absorbing device such that all ordinary shocks of buffing and draft are taken care of by the usual gear or shock absorbing devices and excessive shocks are transmitted to all the longitudinal sills of the car at the ends thereof, the latter effect being accomplished by means of what may be termed a resilient end sill.

Another object of the invention, in one of its forms, is to so arrange the parts that all of the shocks, even those within the capacity of the gear, are transmitted to all of the longitudinal sills of the car as well as the excessive shocks.

Another and more specific object of the invention is to provide an arrangement wherein the stop castings for the gear are resiliently mounted.

The invention furthermore consists in the improvements in the parts and devices and in the novel combinations of the parts and devices herein shown, described and claimed.

In the drawing forming a part of this specification, Figure 1 is a part plan view, part horizontal section of the adjacent ends of two cars in coupled relation and showing my improvements in connection therewith. Fig. 2 is an end elevation of a car structure showing my improvements. Fig. 3 is a broken side elevation of the structure illustrated in Fig. 2. Fig. 4 is a transverse, enlarged sectional view taken substantially on the line 4—4 of Fig. 1. And Fig. 5 is a view similar to Fig. 1, parts being broken away, illustrating another embodiment of the invention.

Referring to the structure illustrated in Figs. 1, 2, 3 and 4, 10—10 denote the channel shaped center sills of a car underframe, 11—11 longitudinal intermediate sills also of channel form, and 12—12 side sills of the underframe. Mounted on the ends of the longitudinally extending sills 10, 11 and 12 are end sill castings 13—13, each of said castings 13 extending from a side sill to the nearest center sill. The castings 13 are each provided with rearwardly extending flanges 14—14 riveted to the corresponding longitudinal sills, said flanges 14 being suitably reinforced by webs 15. The castings 13—13 are provided with parallel, upper and lower horizontal flanges 16—16 between which is slidably mounted a buffer casting 17 which forms a part of the resilient end sill. The casting 17 extends from side to side of the car, but at the center is extended rearwardly in the form of two stop castings or cheek plates 18—18, the latter being integrally united by an upper transversely extending web 19 (see Figs. 2 and 4). Each of the stop castings 14—14 is provided with rear stop shoulders 20 and front stop shoulders 21 to coöperate with the followers of the draft gear proper. Mounted between the stop castings 18—18 is the draft gear which, as shown, is of a well known friction type comprising a combined friction shell and spring casing 22, friction shoes 23 and wedge 24, the latter bearing against a front follower 25. The gear is operatively connected with the draw

bar 26 by a U shaped yoke 27 in a well known manner. The draw bar and gear and also the cheek plates 18 are suitably supported by means of saddle plates 28 and 29.

5 Referring now more particularly to the resilient end sill, it will be noted that the castings 13—13 are each provided with a series of forwardly extending blocks 30—30 equally spaced apart and each having a transversely extending recess 31 therethrough, the bearing faces of said recesses 31 being oppositely convexed as indicated at 32. The member 17 is provided with a corresponding series of rearwardly extended blocks 33—33 spaced so as to fit between the blocks 30, each of said blocks 33 being also provided with a transversely extending recess 34, the bearing faces thereof being also oppositely convexed as indicated at 35. Mounted within the recesses 31 and 34 and extending transversely of the car are a series of relatively heavy plate springs 36, there being two sets of said springs 36, each set extending from the line of the corresponding cheek plate 18 substantially to the side of the car, the springs being held from accidental displacement by bolts 37. The front face of the casting 17 is ribbed as indicated at 38—38 and near the center where the casting 17 is of the greatest depth, the face is made solid as indicated at 39, the structure being such that the parts 39 of two adjacent cars will come into engagement after the gear proper has been actuated.

35 From the preceding description, it will be seen that the cheek plates 18—18 are resiliently mounted, but the strength of the plate springs 36 is such as to prevent movement of the cheek plates 18 during any ordinary blow transmitted to the draft gear proper. As is well known, the permissible movement of the gear parts is determined by standard practice and in my construction, the end sills are so designed that the gear proper will be permitted its full movement before the end sills or buffer castings come into contact. By this arrangement, the gear proper will absorb all ordinary shocks without bringing the heavy spring plates 36 into play. In the event of unusual or excessive shocks being transmitted to the gear, the latter will absorb up to its normal capacity and blows in excess thereof will be absorbed by the plate springs 36, due to the fact that the stop castings or cheek plates will move longitudinally, thus moving the casting 17 relatively to the castings 13, and flexing the springs 36 against the series of convex faces 35. It will be noted that all the shocks transmitted to the gear are distributed to the underframe of the car to the ends of all of the longitudinal sills, thus providing a better structure and eliminating the concentration of the shocks over a relatively small area on the two center sills. The plate springs 36

act, in effect, as an auxiliary shock absorber to take up all the shocks in excess of the normal capacity of the gear proper.

Referring now to the structure illustrated in Fig. 5, 110 denotes the center sills having rear stops 120 and front stops 121 rigidly secured thereto, the stops being so arranged as to coöperate with the gear proper in the usual manner. At the end of the car, 113 denotes the end sill castings rigidly secured to the longitudinal sills (the intermediate and side sills not being illustrated on account of lack of room). Slidably mounted on the castings 113 is the other casting 117 of the end sill, said castings 113 and 117 being provided with a series of over-lapping blocks 130 and 133 transversely recessed and accommodating transversely extending heavy plate springs 136, similarly to the structure illustrated most clearly in Fig. 1.

In the structure illustrated in Fig. 5, all the blows transmitted to the gear proper within the capacity of the latter are transmitted directly to the center sills 110. Blows in excess of the capacity of the gear proper are absorbed by the resilient end sill in the manner above described in connection with the structure illustrated in Fig. 1. More detailed description of the structure in operation illustrated in Fig. 5 is not deemed necessary in view of the prior description of the structure illustrated in the other figures.

Although I have herein shown and described what I now consider the preferred means of carrying out the invention, the same are merely illustrative and I contemplate all changes and modifications that come within the scope of the claims appended hereto.

I claim:

1. In car construction, the combination with an end sill having a cushioned movable member adapted to be actuated upon contact with the end sill of an adjacent car, of a main draft gear carried by said movable member.

2. In car construction, the combination with a car underframe having side and center sills, of a draft gear mounted between the center sills, and means for transferring the shocks from said gear directly to and at the ends of all of said sills.

3. In car construction, the combination with a car underframe having center and intermediate longitudinal sills, of a draft gear mounted between the center sills, and means for transferring the shocks from said gear directly to and at the ends of all of said sills.

4. In car construction, the combination with a car underframe having a plurality of longitudinally extending sills, of castings rigidly secured to the ends of said sills on the opposite sides of the center line of the car, a casting slidably mounted with respect

to said first named castings and cushioned with respect thereto, a draft gear, said movable casting being provided with cheek plates with which the draft gear is coöper-
5 able.

5. In car construction, the combination with a car underframe having a plurality of longitudinally extending sills, of castings rigidly secured to the ends of said sills, said 10 castings being provided with a series of forwardly extended transversely recessed blocks, a buffer casting slidably mounted with respect to the first named castings, the buffer casting being provided with a corre-
15 sponding series of rearwardly extended transversely recessed blocks, and a series of plate springs extending transversely through said recesses.

6. An end sill for cars having longitudinally extending under-frame sills, said end sill comprising, a casting adapted to be rigidly secured to the ends of the longitudinal sills, said casting having a series of outwardly extended, laterally spaced projections, said projections being provided with recesses alined transversely of the car, and an outer casting having inwardly extending, laterally spaced projections alternating with

those of the first named casting and provided also with recesses alined transversely of the 30 car, and spring plates extending through the recesses of the castings and adapted to cushion relative movement between said castings.

7. In car construction, the combination 35 with draft and longitudinally extending sills, of a main shock absorbing mechanism including stop members interposed between the draft sills, and a resilient end sill, said end sill including a casting rigidly attached 40 to said draft and longitudinal sills, a second casting movably mounted with respect to the first named casting, spring means interposed between said castings and adapted to yieldingly resist relative approach or separation 45 of said castings, said stop members of the main shock absorbing mechanism being movable in unison with the said movable casting of the end sill.

In witness that I claim the foregoing I 50 have hereunto subscribed my name this 19th day of Oct. 1916.

JOHN F. O'CONNOR.
